UNITED STATES PATENT OFFICE.

MAX KLEIN, OF BROOKLYN, NEW YORK, ASSIGNOR TO SHAPIRO & ARONSON, INC., OF NEW YORK, N. Y., A CORPORATION OF NEW YORK.

DESIGN FOR A PLATE FOR LIGHTING FIXTURES.

Application filed March 7, 1927. Serial No. 21,023. Term of patent 3½ years.

To all whom it may concern:

Be it known that I, MAX KLEIN, a citizen of the United States, residing in Brooklyn, in the county of Kings and State of New York, have invented a new, original, and ornamental Design for a Plate for Lighting Fixtures, of which the following is a specification, reference being had to the accompanying drawing, forming part thereof, in which—

Fig. 1 is a partial plan view, only part of

the ornamentation being shown, it being understood that the remainder is identical;

Fig. 2 is a side elevation showing my new design, a segment of the plate being omitted to show the configuration of the edge of the plate, the configuration of the center being indicated by the dotted lines.

I claim:

The ornamental design for a plate for lighting fixtures, as shown.

MAX KLEIN.
